[57] CLAIM

The ornamental design for a housing for hors d'oeuvres oven, as shown and described.

DESCRIPTION

FIG. 1 is a front elevational view of a housing for hors d'oeuvres oven showing my new design.

FIG. 2 is a rear elevational view thereof.

FIG. 3 is a side elevational view of one side thereof.

FIG. 4 is a side elevational view of the other side thereof.

FIG. 5 is a top plan view thereof.

FIG. 6 is a side elevational view thereof on a reduced scale similar to FIG. 3 except showing the cover in a partially open position.

FIG. 7 is a side elevational view thereof on a reduced scale showing the cover in a fully open position.
